APPARATUS FOR OPERATING UPON LATERAL WALLS IN EARTH BORINGS

Clyde E. Bannister, Bartlesville, Okla.

Application January 17, 1940, Serial No. 314,198

12 Claims. (Cl. 164—0.7)

This invention relates to apparatus for operating upon a lateral wall in an earth boring, such, for example, as an oil well, as in severing drill-pipe, or the like, unscrewing sections of drill-pipe or the like, or taking a sample of the formation from a lateral wall of the hole.

Some of the features disclosed in the present application are described and claimed in my Re-issue Patent No. 19,397, granted December 18, 1934, as a reissue of my original Patent No. 1,965,563, granted July 10, 1934, and in my pending application Ser. No. 308,978, filed December 13, 1939.

Its chief objects are to provide convenience and economy in the performance of such operations.

Of the accompanying drawings:

Fig. 1 is a view, chiefly in vertical middle section, of apparatus embodying the invention in its preferred form as applied to the severing of a drill-pipe, well-casing, or the like.

Figs. 2, 3 and 4 are elevations of parts that are shown in Fig. 1.

Figs. 5, 6 and 7 are sections on lines of Fig. 1 designated by like section-line numerals respectively.

Fig. 8 is a vertical middle section of the upper portion of a motor that is shown in Fig. 1, inner parts of the same being shown in elevation.

Fig. 9 is a section on line 9—9 of Fig. 1, with parts broken away.

Fig. 10 is a section on line 10—10 of Fig. 9.

Fig. 11 is a section on line 11—11 of Fig. 9.

Fig. 12 is a section at a position corresponding to the line 8—8 of Fig. 1, but showing an alternative type of cutter head.

Fig. 13 is a vertical middle section, with inner parts in elevation, of a preferred embodiment of the invention as applied to the unscrewing of sections of drill-pipe, well-casing, or the like.

Fig. 14 is a section on line 14—14 of Fig. 13.

Fig. 15 is a section on line 15—15 of Fig. 13.

Referring first to Figs. 1 to 10 of the drawings, the assembly there shown comprises a cylindrical motor casing 10 which is screw-threaded at 11 to a heavy inertia barrel 12 adapted to sustain by its inertia the reaction of the shaft-oscillating motor.

Screw-threaded at 15 upon the upper end of the inertia barrel 12 is an inertia-barrel extension in the form of a cylindrical end-closure member 16 formed at its closed upper end with a fluid-inlet neck 17 to which is coupled a hose 18 for supplying fluid to the motor through the space in the inertia barrel 12.

The assembly comprises a pipe-cutter assem-

bly 19 secured upon the lower end of a hollow, oscillating motor shaft 20 which, near the bit, is journaled in the motor casing 10 by means of a radial-and-thrust bearing 21 and also is journaled at 22 in a bulk-head member 23, secured in the motor casing 10 by means such as the cap screws 24, 24, and the shaft also is journaled at 25 in a bulk-head-and-fluid-abutment member 26 (Figs. 1 and 5) which is secured in the motor casing 10 as by means such as the cap screws 27, 27.

Slidably fitting within the motor casing 10 and abutted by shoulders formed on the members 23 and 26 is a removable cylindrical casing-liner 28 of which the inner face (see the right-hand part of Fig. 1) has a sealing fit against an oscillating shaft-impeller 29 which is shown in Fig. 5 as being integral with the motor shaft 20.

The bulk-head-and-fluid-abutment member 26 is formed with an axially long, transversely segmental portion 26a adapted to sustain the reaction of pressure fluid forced between it and the shaft-impeller 29 and the hollow shaft 22, at longitudinally spaced apart positions, is formed with two fluid-inlet ports 30, 31 closely adjacent and at opposite sides of the shaft-impeller 29, and with two fluid-outlet ports 32, 33, closely adjacent and at opposite sides of the shaft-impeller 29.

For putting the said inlet ports, and thus also the chambers at the two sides of the shaft-impeller 29, in communication with the pressure-fluid-chamber in the inertia barrel 12, and for putting the outlet ports in communication with the fluid-discharge passage, which is through the lower end of the hollow motor shaft 20, a hollow oscillatory slide valve member 34 rotatably fits within the hollow motor shaft 20 and is formed with a supply port 35 adapted to be brought into registry with the shaft's port 30, as in Fig. 1 or Fig. 5 and with a supply port 36 adapted to be brought into registry with the shaft's port 31.

Internally the valve member 34 is provided, at a position below the ports 35, 36, with a transverse partition or bulk-head 37 (Fig. 1) and below the partition 37 the valve member 34 is formed, at a circumferential position half-way between those of the ports 35, 36, with an exhaust port 38 adapted to be brought into registry with the shaft's outlet port 33 when the valve's supply port 35 is brought into registry with the shaft's inlet port 30, and to be in registry with the shaft's outlet port 32 when the valve's supply port 36 is in registry with the shaft's inlet port 31.

55

The motor shaft 20 projects a little above the bulk-head-and-fluid abutment member 26 and upon its projecting end portion is secured by means such as the set-screw 39 a cup-shaped pressure-chamber member 40 provided with a threaded end-closure member 41.

The valve member 34 extends with a sealing fit through the end closure member 41 and a bulk-head member 42 which is secured in the motor casing 10 by means such as the cap-screw 43 and within the pressure-chamber member 40 the valve member 34 is formed with annular shoulders 44, 45 abutting respectively the end of the motor shaft 20 and the closure member 41 to hold the valve member in position axially.

In that region also the valve member 34 is formed with fluid-inlet ports 46, 47 opening on opposite sides of a valve impeller 48 formed integrally with the valve and internally the cup-shaped pressure-chamber member 40 is provided with a fluid-abutment 49 to sustain the reaction of fluid actuating the valve-impeller 48, the fluid-abutment 49 being, through the pressure-chamber member 40, rigid with the motor shaft 20.

The valve-impeller 48, integral with the valve 34, is free to rotate with relation to the motor shaft only through the small arc permitted by stops 50, 51 (Fig. 6) mounted on the lower end wall of the pressure-chamber member 40.

For supplying pressure fluid alternately to the fluid chambers on the respective sides of the valve impeller (Fig. 6) a hollow pilot-valve member 52 (Figs. 1, 4, 6 and 7) comprises a stop-lug head portion 53 and a cylindrical valve portion 54 which is formed with a port 55 adapted to be brought into registry with the port 46, as in Fig. 6, when the stop-lug head portion 53 of the member 52, in one direction of rotation, is stopped by a stop-pin 56 mounted upon the bulk-head 42; and with a port 57 adapted to be brought into registry with the port 47 when the portion 53 of the member 52 is stopped, in the opposite direction of rotation, by the stop-pin 56.

The cup-shaped pressure-chamber member 40 is formed at appropriate positions with vent ports 58, 59 and for opening and closing them at proper times a valve sleeve 60 is mounted upon the member 40 and formed with vent ports 61, 62 and with shoulders such as the shoulder 63 (Fig. 8) adapted to strike a stop-pin 64 projecting from the bulk-head 26, at proper times.

The fit of the valve 34 within the motor shaft 20, the fit of the pilot valve 52 in the valve 34, and the fit of the valve-sleeve 60 upon the member 40, are such that all of these parts just mentioned rotate together, by reason of their frictional engagement, except as they are oscillated with relation to one another by the stops described or by pressure fluid acting between the valve-impeller 48 and its fluid-abutment 49.

In the operation of the motor, assuming the shaft-impeller 29 to have moved clockwise, as viewed in Fig. 5, to the position in which it is there shown, contact of the stop-lug portion 53 of the member 52 with the stop-pin 56, as in Fig. 7, has brought the port 55 into registry with the port 46, as in Fig. 6, and pressure fluid passing through those registered ports, with the vent ports 59 and 62 out of registry and the vent ports 58, 61 in registry (Figs. 6 and 8), has quickly moved the valve-impeller 48 from the stop 51 to the stop 50, and this has put the valve port 35 in registry with the shaft port 30, as in Fig. 5 and the exhaust port 38 of the valve in registry with the outlet port

33 of the motor shaft. When the valve impeller 48 is thus quickly moved from the stop 51 to the stop 50, Fig. 6, the valve member 34 has carried with it in its rotation, by reason of the frictional fit, the pilot valve 52, and then both of them, by reason of the frictional fits, rotate with the motor shaft until near the end of its counter clockwise movement, at which time contact of the stop-lug 53 with the pin 56 and contact of one of the shoulders 63 (Fig. 8) with the pin 64 reverses the valve setting of the pilot valve 52 and valve sleeve 60 with the result that the main valve 34 is likewise reversed as to port registries, by the forcing of the valve-impeller 48 clockwise as viewed in Fig. 6, into contact with the stop pin 51, the valve 34 again frictionally carrying with it, clockwise, the pilot valve 52.

The cycle as just described is then repeated continuously so long as motive fluid is forced into the assembly.

As the reversal of registries of inlet ports and the reversal of registries of outlet ports controlling the movement of the valve-impeller 48 are simultaneous, and as the only resistance to oscillation of the valve 34 is a small frictional resistance, and as the shaft-impeller is still being driven in one direction until its direction has been reversed by reverse movement of the valve-impeller 48, and as any unbalance of fluid pressure starting the reverse movement of the valve-impeller 48 will inevitably complete its movement, the motor is without any dead-center position of its parts.

Secured upon the lower end of the motor shaft 20 is an oscillatory pipe-cutter assembly comprising a spider 65 having three forked arms in each of which is pivoted, at 66, a rocker member 67 having two arms each formed with a cutter portion 67^a, and each of said arms has a forked extension 67^b in which is journaled a roller 68, these rollers being adapted to prevent the cutters from biting too deeply into the pipe 69, as the spider 65 is rapidly oscillated by the oscillating motor shaft 20 upon which it is mounted, the center of gravity of each rocker member 67 being farther from the axis of the assembly than the rocker member's pivot 66 so that in each reversal of the direction of the assembly's rotative movement the inertia of the rocker assembly causes it to be relatively rotated on its pivot to bring the leading one of its cutters 67^a into contact with the inner face of the drill pipe 69, resistance of the cutter's contact with the pipe then causing the cutter to stay in cutting position and the roller 68 to press more forcibly against the pipe, throughout the rotative movement of the cutter assembly in the reversed direction.

Thus the pipe is quickly severed, and at such position as can readily be controlled according to the depth to which the assembly is lowered in the hole.

Preferably each of the cutters 67^a is formed with its sides beveled at an angle, about as shown in Fig. 10, such that after the pipe is severed a slight raising or lowering of the assembly, or repeated slight vertical reciprocation of it, will by cam action of the cut faces of the pipe against the bevel faces of the cutters, cause the rocker members 67 to assume substantially symmetrical positions with relation to the radii through their pivots, to permit the assembly to be withdrawn to the top of the ground, or to be moved to a different elevation for another cutting operation. Preferably the rollers 68 are peripherally beveled at the same angle as that of the bevels of the cutters, for

firm and stable bearing of the rollers against the cut surfaces.

In Fig. 12 is shown a modified type of cutter-head assembly in which the cutters are in the form of ratchet wheels 69^a, 69^b and springs 69^c, 69^d are so mounted on the spider as to bear upon the inclined faces of the ratchet teeth and resist rotation of the cutter on its own axis but only with such force as to permit the cutter so to rotate in case of excessively deep biting of the cutter into the pipe, in which case the next tooth of the cutter comes into cutting position and the spring bears upon the next one of the inclined faces on the next tooth.

In Fig. 13 is shown an assembly adapted for uncoupling lengths of drill pipe 70, 71 which are joined by a threaded coupling 72, this assembly comprising an oscillatory motor 73 substantially like that shown in Fig. 1, the oscillatory motor shaft thereof being shown at 74, and a round-nosed, guiding and inertia member 75 being mounted on the lower end of the motor shaft, the inertia member 75 preferably being of about the same weight as the motor assembly, so that, if it be assumed that the motor were being operated idly, the motor assembly and the inertia member 75 would oscillate with about the same amplitude, although this is not at all an indispensable feature of the invention.

Secured to the casing of the motor as by cap-screws 76, 76 is a head 77 through which the motor shaft 74 rotatably extends. The head 77 is formed with a circumferential series of peripheral recesses, 78, 78, in each of which is pivoted, at 79, a toothed pawl 80, the pawls having their centers of gravity radially outward of their pivots so that in counter-clockwise movement of the head with the motor casing assembly (Fig. 14) the pawls 80 will engage and bite into the inner face of the drill-pipe section 70 and rotate it, but will release it and run free in clockwise movement of the head.

Secured to the inertia member 75, as by cap-screws 81, 81, is a head 82 which is likewise provided with pawls 83, 83, except that these pawls are adapted to bite into the inner face of the drill-pipe section 71 and rotate it in clockwise movement of the head 82, and to run free in counter-clockwise movement of the head.

In the operation of this assembly, when it has been brought to the proper elevation in the hole and the motor started, the two sets of pawls 80 and 83 engage the respective pipe sections 70 and 71 and by their oscillatory movements effect such relative rotary motion of the pipe sections as to unscrew one or the other of them from the coupling 72, according to which of the two sets of threads yields the easier, except as that factor may be off-set by the relative inertias of the portions of the drill string that are constrained to rotate with the pipe sections 70 and 71 respectively and by the relative masses of the motor assembly and of the member 75. Usually it is desired to have the upper pipe section 70 and the sections above it rotate for the unscrewing operation while the lower pipe section 71 and the sections below it are not substantially rotated, and for this it is desirable that the inertia member 75 be of appropriate weight, but my invention is not wholly limited to that feature, nor is it wholly limited to the unscrewing of pipe as distinguished from the setting up of the pipe sections in the couplings or in tool joints.

The motive-fluid-supply conduit, 78^a, can be either a hose or a line of pipe.

Preferably the two sets of pawls are spaced apart vertically a sufficient distance to make unnecessary very close accuracy as to the positioning of the assembly.

Modifications of the several assemblies are possible without departure from the scope of the invention as defined in the appended claims.

I claim:

1. The combination of a motor of the shaft-oscillating type, inertia means for sustaining the reaction of the motor, and laterally directed and laterally urged means coaxial with and oscillated by the motor for operating upon a lateral wall in a previously formed earth boring.
2. The combination of a motor of the shaft-oscillating type, inertia means for sustaining the reaction of the motor, and laterally directed and laterally urged means mounted upon and oscillating with the shaft of the motor and coaxial with the motor for operating upon a lateral wall in a previously formed earth boring.
3. The combination of a motor of the shaft-oscillating type and a laterally acting cutting tool mounted upon the shaft of and coaxial with the motor.
4. The combination of a rotatably mounted member and a cutting device so mounted thereon as to be moved radially outward into cutting engagement with the work solely by its inertia as an incident of being accelerated in rotative movement of said member.
5. The combination of a rotatably mounted member and a cutting device so pivotally mounted thereon as to be moved radially outward into cutting engagement with the work solely by its inertia as an incident of being accelerated in rotative movement of said member.
6. Apparatus for severing a tubular member from within, said apparatus comprising a rotatably mounted member adapted to be positioned in the tubular member and a cutting device so mounted thereon as to be urged radially outward, as an incident of rotative movement of said member, by the resistance of its contact with the work.
7. Apparatus for severing a tubular member from within, said apparatus comprising a motor of the shaft-oscillating type adapted to be positioned in the tubular member and a circumferential series of cutting devices having such connection to the shaft of the motor as to oscillate therewith and to be urged outward in cutting relation to the work by the oscillation.
8. The combination of a motor of the shaft-oscillating type, a set of gripper pawls constrained to oscillate with the casing of the motor and constructed and arranged to grip the work in one direction of movement with relation to the work and a set of gripper pawls constrained to oscillate with the shaft of the motor and constructed and arranged to grip the work in the other direction of movement in relation to the work.
9. The combination of a motor of the shaft-oscillating type and oppositely faced sets of gripper pawls mounted on the motor and on its shaft respectively.
10. The combination of a motor of the shaft-oscillating type, oppositely faced sets of gripper pawls mounted on the motor and on its shaft respectively, and inertia means for resisting oscillation of the shaft.
11. The combination of a motor of the shaft-oscillating type and oppositely faced sets of gripper pawls mounted on the motor and on its

shaft respectively, the pawls being pivoted and having their centers of gravity radially outward of their pivots so that their inertia causes them to be rotated on their pivots by rotative acceleration of the assembly.

12. The combination of a motor of the shaft-oscillating type and oppositely faced sets of

gripper pawls mounted on the motor and on its shaft respectively, the pawls being so constructed and arranged that their work-engaging portions are moved outward from the axis of rotation by centrifugal force in rotative movement of the assembly.

CLYDE E. BANNISTER.
